[57] CLAIM

The ornamental design for a shoe outsole, as shown and described.

DESCRIPTION

FIG. 1 is a bottom plan view of a shoe outsole showing my new design;

FIG. 2 is a cross-section generally along line 2—2 in FIG. 1;

FIG. 3 is a side elevational view of one side of the outsole shown in FIG. 1; and,

FIG. 4 is a side elevational view of the other side of the outsole shown in FIG. 1.

The broken line showing of a shoe upper and midsole are environmental only and forms no part of the claimed design.
